Fraenzer & Richards,
ATTORNEYS.

UNITED STATES PATENT OFFICE.

WILMER C. STALEY, OF TIPPECANOE CITY, OHIO.

PULP BEATING OR BREAKING MACHINE.

Application filed November 20, 1924. Serial No. 750,988.

To all whom it may concern:

Be it known that I, WILMER C. STALEY, a citizen of the United States, residing at Tippecanoe City, in the county of Miami and 5 State of Ohio, have invented certain new and useful Improvements in Pulp Beating or Breaking Machines; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification.

This invention relates, generally, to improvements in pulp beating or breaking machines commonly employed in the paper making industry; and the invention has reference, more particularly, to a novel construction and arrangement of pulp beating or breaking machine in which the backfall is subject to adjustment.

The invention has for its principal object to provide, in connection with a pulp beating or breaking engine or machine, a novel arrangement and construction of backfall having means for producing desired vertical adjustment thereof, whereby the height 20 and position of the backfall relative to the beater roll may be selectively determined, so that the same may be adjusted to the best point to take full advantage of the centrifugal action of the roll, to the end that the speed of circulation of the pulp by the mechanism may be regulated to the most efficient degree, and a maximum speed of circulation commensurate with efficient pulp beating action be attained.

Other objects of this invention, not at this time more particularly enumerated, will be clearly understood from the following detailed description of the same.

The invention consists, primarily, in the novel construction of beater or breaker having an adjustable backfall as hereinafter set forth; and, the invention consists, furthermore, in the novel arrangements and combinations of the various devices and parts, as well as in the details of the construction of said parts, all of which will be

hereinafter more fully described, and then finally embodied in the appended claims.

The invention is clearly illustrated in the accompanying drawings, in which:

Figure 1 is fragmentary vertical longitudinal section of a portion of a beating or breaking engine or machine, illustrating the construction and arrangement of the novel adjustable backfall, made according to and 60 embodying the principles of this invention; and Figure 2 is a fragmentary transverse section through the same, taken on line 2—2 in said Figure 1.

Similar characters of reference are employed in all of the hereinabove described views, to indicate corresponding parts.

Referring now to said drawings, the reference character 3 indicates the usual beater trough or tub in which the beater mechanism 70 is mounted, and in which the raw material to be pulped, and the water for softening the same and assisting its circulation around the tub or trough to the beater roll, is received. Arranged within the trough or tub is the 75 usual mid-feather 4 which terminates short of each end of the trough or tub, and which serves to properly divide the interior of the latter to provide the usual continuous circulatory passage therein. Mounted on a 80 suitably journaled transverse drive shaft 5, so as to be disposed intermediate one side wall and the mid-feather 4, is the usual beater roll 6. Said beater roll is provided, around its circumference, with a plurality 85 of radially projecting fly-bars 7. Arranged beneath said beater roll is a suitable base-plate 8 provided with upwardly projecting stationary or plate knives 9 with which the fly-bars 7 of the beater roll cooperate in 90 teasing or beating out the pulp.

Extending upwardly and forwardly from the base-plate 8, and substantially concentric to the forward quarter of the underside of said beater roll, is a stationary apron-frame 10 disposed transversely intermediate one side of the trough or tub 3 and its mid-feather 4. Spaced forwardly from the upper free end of said apron-frame 10 is a stationary bridge-plate 11, which also extends transversely between one side of the trough or tub 3 and its mid-feather 4, in

suitably fixed connection therewith. Said bridge-plate 11 is provided at its upper margin with a forwardly and downwardly inclined flange 12, to which is secured a forwardly and downwardly sloping fixed backfall plate 13.

The spaced apart relation of said bridge-plate 11 to said apron-frame 10 provides an intermediate substantially vertical slideway 14. Vertically movable in said slideway 14 is an adjustable backfall member 15 provided at its upper margin with a forwardly and downwardly sloping backfall flange 16. The lower marginal portion of said adjustable backfall member 15 is provided with at least one, but preferably two or more outwardly projecting internally screw threaded lugs 17 in which are engaged corresponding elevator screws 18. Suitably secured in the bottom of said trough or tub beneath said adjustable backfall member 15 is a bearing plate 19 provided with suitable thrust-bearing members 20 for supporting the lower ends of said elevator screws 8. Said bearing plate 19 is provided with additional bearing members 21 in which is journaled and between which extends a transverse shaft 22 offset to one side of said elevator screws 18. Fixed on said transverse shaft 22 are worms 23 which mesh with and drive the worm gear 24 with which the lower ends of said elevator screws are provided. One end of said transverse shaft 22 projects exteriorly through the adjacent side wall of the trough or tub 3, through a stuffing-box 25 fixed in the latter. The exterior end of said transverse shaft may be provided with a squared end 26 for the application thereto of a crank-handle (not shown), by means of which said shaft may be rotated to in turn rotate said elevator screws; it will be understood, however, that any other arrangement or means found convenient for applying power to said transverse shaft 22 may be utilized. If desired, the lower marginal portions of said bridge-plate 11 may be cut away, as at 27, to permit clearance for the lugs 17 of the adjustable backfall member.

The reference character 28 indicates any suitable form of beater roll cover or inclosing hood with which pulp beaters are usually provided.

By rotating the shaft 22, in desired direction, power may be applied to turn the elevator screws 18, to thereby either raise or lower the adjustable backfall member 15 and its flange 16, as may be desired. It will thus be apparent that the height of the backfall means as a whole is subject to selective adjustment, whereby its position may be fixed at whatever point is found to be most advantageous for efficient cooperation with the beater roll, to the end that thorough beating out of the pulp may be rapidly accomplished, and the speed of circulation of

the pulp and water around the trough or tub maintained at the most efficient degree.

I am aware that some changes may be made in the general arrangements and combinations of the devices and parts, as well as in the details of the construction of the same, without departing from the scope of my invention as described in the foregoing specification, and as defined in the claims appended hereto. Hence, I do not limit my invention to the exact arrangements and combinations of the devices and parts as set forth in the foregoing specification, nor do I confine myself to the exact details of the construction of said parts as illustrated in the accompanying drawings.

I claim:—

1. In a pulp beater or breaker, the combination with the beater roll of a stationary apron frame forwardly spaced from and substantially concentric to said roll, a transverse bridge-plate adjacent to the upper end of said apron frame and spaced therefrom to provide an intermediate substantially vertical slideway, a fixed downwardly and forwardly inclined backfall plate supported by said bridge-plate, an adjustable backfall member movable in said slideway, said backfall member having at its upper free margin a downwardly and forwardly inclined backfall flange, and means for raising and lowering said backfall member to adjust the height of the same.

2. In a pulp beater or breaker, the combination with the beater roll of a stationary apron frame forwardly spaced from and substantially concentric to said roll, a transverse bridge-plate adjacent to the upper end of said apron frame and spaced therefrom to provide an intermediate substantially vertical slideway, a fixed downwardly and forwardly inclined backfall plate supported by said bridge-plate, an adjustable backfall member movable in said slideway, said backfall member having at its upper free margin a downwardly and forwardly inclined backfall flange, internally threaded means connected with said backfall member, screw means engaged with said internally threaded means, and means for rotating said screw means in either direction to raise and lower said backfall member as may be desired.

3. In a pulp beater or breaker, the combination with the beater roll of a stationary apron frame forwardly spaced from and substantially concentric to said roll, a transverse bridge-plate adjacent to the upper end of said apron frame and spaced therefrom to provide an intermediate substantially vertical slideway, a fixed downwardly and forwardly inclined backfall plate supported by said bridge-plate, an adjustable backfall member movable in said slideway, said backfall member having at its upper free margin a downwardly and forwardly

inclined backfall flange, internally threaded means connected with said backfall member, screw means engaged with said internally threaded means, and means for rotating said screw means in either direction to raise and lower said backfall member as may be desired, comprising a transverse

rotatable shaft, and a worm and gear transmission means intermediate said transverse shaft and said screw means. 10

In testimony that I claim the invention set forth above I have hereunto set my hand this 13th day of November 1924.

WILMER C. STALEY.
